UNITED STATES PATENT OFFICE.

HENRY W. POTTEIGER AND WILLIAM A. KOHMAN, OF READING,
PENNSYLVANIA.

DESIGN FOR A CLOTHES-POUNDER.

SPECIFICATION forming part of Design No. 23,357, dated June 12, 1894.

Application filed May 1, 1894. Serial No. 509,722. Term of patent 3½ years.

To all whom it may concern:

Be it known that we, HENRY W. POTTEIGER and WILLIAM A. KOHMAN, citizens of the United States, residing at Reading, in the county of Berks and State of Pennsylvania, have invented and produced a new and original Design for a Pounder, of which the following is a specification.

The accompanying drawing forming a part of this specification, represents a plan view of the pounder embodying our design.

The leading feature of our design consists in the cruciform head, the arms of which are bodily tapered inwardly, presenting longitudinally ranging diverging raised figures *a*, disposed in circular series at the peripheries of the arms, the side surfaces *b* of said figures converging and the ends being beveled, said ends presenting triangular figures *a'*, the longitudinally ranging elongated triangular

figures *c* alternating with the figures *a* at the bases of such raised figures *a*, the many sided ring-like figures *d* joining the figures *a* *c* at the outer terminals thereof, the circular figures *e* at the inner ends of the figures *a*, such figures *e* of the several arms appearing at four sides of a central spherical figure *f* and joined to the same by truncated cone figures *g*, said figures *e*, *f*, *g*, presenting as viewed in plan a generally cruciform figure at the center of the pounder.

We claim—

The design for a pounder herein shown and described.

HENRY W. POTTEIGER.
WILLIAM A. KOHMAN.
